SIDE DOOR FOR RAILWAY CARS

Karl F. Nystrom, Chicago, Ill., assignor to Standard Railway Equipment Manufacturing Company, Chicago, Ill., a corporation of Delaware

Application August 4, 1950, Serial No. 177,671

5 Claims. (Cl. 20—22)

This invention relates to side doors for railway box cars which ordinarily roll upon rollers fixed to opposite lower outer margins of the door, which rollers roll upon a horizontally disposed track fixed to the car below the door opening. The travel of such doors is approximately equal to the width of the door opening so that the door may be moved to a position opposite the door opening for closing the same, or from such position to a position to one side of said opening so that the opening is entirely clear.

The invention more specifically relates to the bottom door rail supporting the rollers, and to the arrangement of the track, secured to the side sill and side sill reinforcement, whereby the track also functions as a reinforcement for the side sill. The invention also relates to details of construction which will hereinafter more fully appear.

Referring now to the accompanying drawing forming part of this application, wherein like reference characters indicate like parts:

Fig. 1 is a side elevation of a car door and portion of a car track embodying the invention.

Fig. 2 is a vertical section through the car door.

Fig. 3 is a transverse section through the door.

Fig. 4 is an enlarged vertical section through the door and doorway of the car.

Fig. 5 is a side elevation of the door frame and track arrangement.

Fig. 6 is a section on line 6—6, Fig. 5.

Fig. 7 is a section on line 7—7, Fig. 5, slightly enlarged.

Fig. 8 is an end view of the door track, slightly enlarged.

Fig. 9 is a section on line 9—9, Fig. 5, slightly enlarged.

Fig. 10 is a section on line 10—10, Fig. 5, slightly enlarged.

In the drawings a portion of a railway car is shown having a side plate 2, side sill 3, each of which extends from corner post to corner post, and vertical door posts, 4 front and 5 rear, extending between and secured to plate 2 and sill 3. Side sill 3 is a part of the underframe of the car and in this instance comprises an angle iron having a relatively long leg disposed horizontally and a relatively short leg disposed vertically. Under the doorway 6 of the car there is a reinforcing bulb angle 7 with the web thereof disposed vertically and in plane with the vertical leg of sill 3, with a leg disposed horizontally and abutting the longer leg of sill 3, and secured thereto by a row of rivets, one of which is indicated at 8. This bulb angle extends under the doorway and to one side thereof a distance approximating the width of the doorway.

The door track comprises a channel member, the web of which is indicated at 9, which web is provided with a row of holes 10 for application of plug welds in securing said track to bulb angle 7. Along the top inner

2

corner of the track there is a weld 11 securing the track also to sill 3. Bottom flange 12 of the track is provided with three spaced slots 13, two of which occur approximately under the door posts and the other at the end of the track remote from the doorway, all being spaced apart approximately the width of the door. Slots 13 have tapering ends, as shown, the purpose of which will appear later. Upper flange 14 extends outwardly from web 9 and terminates in a downturned reflare 15.

10 An alternate means of attaching the web 9 to the side sill 3 and bulb angle 7 is indicated, in dotted lines, as comprising rivets 16 and 17.

The wood floor of the car is indicated at 18 as resting upon and supported by side sill 3. The car threshold plate is shown at 19, being welded along its outer edge, as at 20, to flange 14 and extending inwardly over vertical flange of sill 3 and floor 18. The flange 14 is the top of an outwardly facing channel attached at its web 9 to the side sill 3, the channel terminating in the bottom flange 12. The top flange 14 terminates in the downturned reflare 15.

15 The door track being secured to the sill 3 and reinforcing member 7, as described, forms, in addition to its function as a track, additional reinforcement for the side sill 3 and support for said bulb angle.

20 Across the top of the door opening is secured thereto a guide or sealing strip comprising a vertical portion 25 abutting side plate 2 and having a horizontal outturned portion 26 and a downturned portion 27 which terminates in an upwardly facing U-shaped portion 28 having a reflare 28' which is substantially coplanar with the inner surface of the vertical sheets forming the inner wall of the door at 60, 61 and 62. The lower margin of portion 25 is outwardly and downwardly inclined, as at 29, and then turned inwardly horizontally, as at 30, the edge of which is welded to the side plate 2, as at 31. Also, portion 25 is welded to side plate 2, as at 32. The parts 25 to 30 coact to form a hood. The top rail of the door comprises a vertical portion 35 secured along its lower margin to top margin of door sheet 62, which portion 35 is inwardly inclined, along a substantially central portion thereof as at 37, parallel with portion 29 and then extends upwardly in a vertical wall 37' and terminates in a downwardly facing U-shaped portion 38 constituting a reflare 38' which interlocks loosely with the reflare 28' of the U-portion 28, so as to permit limited vertical and lateral movement of the door, as well as horizontal sliding movement thereof. Vertical wall 37' is displaced inwardly from the plane of the inner surface of the vertical sheets forming the inner wall of the door at 60, 61 and 62, in a position which extends in spaced parallel relation to the downwardly directed reflare 38'. The reflare 28' that is directed upwardly is disposed in a plane that is spaced parallel to the plane of the downturned portion 27. The reflanges 38' and 28' interengage so that as the door moves longitudinally the door is also free to move laterally as inclined surface 37 slides on inclined surface 29. The inclined surface 37 is supported in spaced relation to side plate 2 by the inwardly horizontally extending portion 39 of the guide or sealing strip. Thus when the door is lowered until portion 37 contacts portion 29, a further lowering of the door will cause portion 37 to slide outwardly on portion 29, until the sealing members (hereinafter described) at the vertical side margins of the door come into engagement.

25 The bottom door rail comprises a vertically disposed portion 40 secured to the lower margin of lower door sheet 60 and is outwardly and downwardly inclined, as at 41, to the outer plane of the door, thence turned downwardly, as at 42, parallel with reflare 15, thence

inwardly, as at 43, parallel with flange 14 and thence downwardly, as at 44, parallel with portion 42, the lower edge of portion 44 being spaced from flange 12. At the outer lower corners of the door, portions 43 and 44 are cut away to permit installation of roller housing 45 which is welded thereto, as at 46, at both ends. Roller housing 45 is provided with roller 47 journaled on pin 48 so that roller 47 may roll upon track flange 12 at all times except when rollers 47 drop into depressions or slots 13, at which time the rollers are relieved of the weight of the door and the bottom of the door rests upon flange 12. When the door is thus lowered, inclined portion 41 rides on arcuate corner between flange 14 and reflare 15 causing lower margin of door to be moved outwardly, coincident with the outward movement of the upper margin of the door, above-described.

The spacing of the slots 13 is such that when the door is in closed position the rollers are in the slots under the vertical margins of the door opening, and when the door is in fully opened position, said rollers are in the slot under the rear vertical margin of the door opening and the slot remote from the door opening. At the rear end of the door track and at the rear end of the top guide or sealing strip are closing strips which are welded to the ends of the door track and top guide, respectively, after the door is installed, so that the door cannot run off the rear end of the track accidentally.

Upon the track 12, approximately under the vertical center of the door opening, there is installed a door support comprising an angular shaped plate member 50 having a horizontal surface underlapping track flange 12 and a vertical surface extending substantially in plane with outer edge of flange 12. Plate member 50 has its upper inner corner cut away providing an inclined surface 51 which assists in guiding the door during vertical movements thereof. Plate member 50 is provided with a pair of laterally projecting wings 52—52 which are welded to plate 50 and to edge of flange 12 to reinforce plate member 50 against distortion due to bumps or the like. This door support provides a guide for the lower edge of the door during horizontal sliding thereof on track 12 and acts as a reinforcement for the bottom door rail when said rail is subject to bulging under bulk commodity loading.

The door posts 4 and 5 are provided with sealing strips 55 and 56, respectively, which are of conventional design. Strip 55 is welded to front door post 4 and is provided with a hook portion 57. Rear strip 56 is likewise secured to rear door post 5 and has an outwardly and rearwardly turned portion 58. The door itself is made up of a plurality of sheets 60, 61 and 62 extending crosswise of the door, the meeting side margins of which overlap and are secured together by welding. The door sheets are reinforced by vertically spaced, horizontal channel members 63 which extend between the front 64 and rear 65 door stiles, each of which comprises a Z-shaped member, the webs 66 and 67, respectively, of which are welded to the respective ends of said member 63 and the outer legs of which members 64 and 65 overlap the ends of said members 63 and are secured thereto. The door sheets 60, 61 and 62 lie flatly against and are secured to the inner legs 68 and 69 of said stiles. The front stile leg 68 has an outwardly turned arcuate portion 70 for engagement within similarly shaped portion 67 when the door is closed. The rear stile leg 69 has an inwardly turned arcuate portion 71 for engagement with flange 58 when the door is closed.

A long starting lever slot bar 75 is secured to bottom flange 12, edge to edge, so as to project outwardly therefrom, as shown clearly in Fig. 6, and comprises a flat bar having a plurality of spaced holes 76 therein. Bar 75 is located on the track so as to occur directly under the door starting lever 77. Door starting lever 77 is tapered and the enlarged end is provided with an elongated slot 78 and a tongue 79 extending from the en-

larged end. A bracket 80 is secured to the door near the bottom and to the rear of the vertical center of the door, and said lever is pivoted thereto by a rivet 81 passing through said elongated slot so that said lever may pivot on said rivet and reciprocate thereon within the limits of the length of said slot. The location of said bracket in relation to said slot bar 75, when the door is closed as shown in Fig. 1, is such that when the lever is swung clockwise on rivet 81, tongue 79 will engage in one of said holes 76 and by engaging said holes successively said door may be forced open. When the door is to be forced to fully closed position the same procedure is followed except that the handle is moved in an anti-clockwise direction in engaging said holes 76.

To assure that the handle is spaced from said door when being operated a combined lever guide and handle 85 is secured to said door in the path of movement of said handle, which guide and handle may be used to move the door manually after being started in either direction by said lever.

A smaller slot bar 86 with one opening 87 therein is similarly secured to the track flange 12 and this bar is placed so that it may be engaged by the lever to start the door moving from fully open position toward closed position.

At the rear end of the track 12 is a bumper plate 90 which extends between and is welded to flanges 14 and 12 of the track. This plate is welded in place after the door is on the car and prevents the door from running endwise off the track.

A similar plate 91 is welded to the rear end of the top guide and sealing strip for a like purpose.

I claim:

1. In a hood structure for a vertically shiftable and laterally movable door for a railway car wall having a door frame therein wherein the door terminates in a door frame member including a substantially centrally disposed downwardly and inwardly inclined portion, the top marginal periphery of said door frame member terminating in an outwardly and downwardly extending U-shaped portion having a reflare disposed in substantially parallel spaced relation to the plane of said door frame member, a side plate, a hood having a vertically disposed central portion supported on said side plate, said vertically disposed portion of said hood having a bottom peripheral portion that is inclined outwardly and downwardly for forming a surface for slidably supporting said aforementioned substantially centrally disposed downwardly and inwardly inclined portion of said door frame member, an inturned substantially horizontally extending marginal portion connected with the bottom peripheral portion of said hood and secured to said side plate for supporting the bottom peripheral portion of said hood in said outwardly and downwardly inclined position, the upper portion of said hood extending above said U-shaped portion of said door frame member and over and beyond the reflare thereon and projecting downwardly beyond the terminating edge of said reflare on said door frame member in substantially parallel spaced vertical relation thereto, the said downwardly extending portion of said hood being reversed upon itself and extending upwardly in spaced parallel relation to said door frame member in a reflare engaging the reflare of said door frame member and supporting said door frame member in a position free to shift vertically while moving laterally as the inclined surface on said door frame member slides outwardly or inwardly on the supporting inclined surface on said hood in relation to the door frame in the car wall.

2. A hood structure for a vertically shiftable and laterally movable door for a railway car wall having a door frame therein as set forth in claim 1 in which the downwardly extending portion of the hood projects across the front of the vertically disposed central portion of said

hood approximately one half the vertical depth of said hood.

3. A hood structure for a vertically shiftable and laterally movable door for a railway car wall having a door frame therein as set forth in claim 1 in which the outwardly and downwardly extending portion of the hood terminates at the front of the hood in a position above the coacting inclined surfaces of said door frame member and said hood.

4. A hood structure for a vertically shiftable and laterally movable door for a railway car wall having a door frame therein as set forth in claim 1 in which the inturned substantially horizontally extending marginal portion of said hood is integrally connected with the substantially centrally vertically disposed portion of said hood along one edge and abuts in a welded connection with said side plate along the other edge thereof.

5. A hood structure for a vertically shiftable and laterally movable door for a railway car wall having a door frame therein as set forth in claim 1 in which the reflare on the inwardly and downwardly extending U-shaped portion of said door frame member extends in a plane

that is substantially coplanar with the plane of the inner wall of the laterally movable door.
